UNITED STATES PATENT OFFICE.

JOHANN HUGO AXIEN, OF HAMBURG, GERMANY.

BLOWER.

1,092,132.

Specification of Letters Patent.

Patented Apr. 7, 1914.

Application filed November 25, 1912. Serial No. 733,469.

To all whom it may concern:

Be it known that I, JOHANN HUGO AXIEN, subject of the German Emperor, residing at Nos. 29/31 Flachsland, in the city of Hamburg, German Empire, have invented new and useful Improvements in Blowers; and I do hereby declare the following to be a full, clear, and exact description of the same.

My invention relates to a blower (for example of the Root type) in which the air, or other medium, such as a gas or liquid, sucked in is forced by means of a blade, which is so moved in close contact with the inner surface of the blower casing that it always separates the suction and pressure chambers. In the blowers of this kind heretofore used the operation was accompanied by a very unpleasant mechanical noise. According to my invention this noise is avoided by the force blade being guided at all parts, for which purpose I connect both ends of the blade with suitable organs. I prefer to connect one end of the force blade to a crank pin which moves on a path concentric to the bore of the blower casing, while the other end of the force blade is hinged to an oscillating arm the axis of which is inside the blower casing. It is then possible to avoid working surfaces inside the casing which require lubrication and accordingly give occasion to the very considerable defect that the lubricant is taken away by the forced air.

On the drawing an embodiment of the invention is shown by way of example.

In all figures similar parts are designated by the same reference characters.

Figure 1 is a side elevation of one construction of the blower; Fig. 2 is a section of an explanatory device; Fig. 3 is a corresponding section showing the blade in another position; Fig. 4 is a vertical section on the line C—D in Fig. 2; Fig. 5 is a section on the line A—B of Fig. 1.

The invention as claimed is illustrated by Figs. 1 and 5. The features of the invention will first be explained relative to Figs. 1 to 4 which are for purposes of explanation only.

The casing of the blower, in the construction shown in Figs. 1-4, consists of a middle part 1 having a cylindrical bore 2, a foundation plate 3 and two covers 4 and 5. In the cover 5 is journaled the shaft 6 which carries a driving pulley 7 and is journaled at its other end in the bearing 8. On the

inner end of the shaft 6 is fastened a disk 9, which carries the crank pin 10. On this crank pin turns the bored end 11 of the blade 12, so that said blade can be turned about the pin 10. Through the opposite end 13 of said blade, which is also bored, passes a bolt 14 which projects into the eyes 15 of the oscillating arm 16. Between the blade 12 and the blade 16 there is therefore a hinge connection. The other end 17 of the arm 16 turns about the bolt 18.

If the disk 9 is rotated by the shaft 6 the crank pin 10 and the end 11 of the blade will be correspondingly moved. As the opposite end of the blade is hinged to the oscillating blade 16 it cannot describe a rotary movement, but will receive a peculiar swinging motion which is utilized to cause the air entering through the socket 19 to be pressed out through the socket 20. In Fig. 2 the blade 12 in the position I has just cut off communication between the cylinder 2 and the inlet socket 19. On further rotating the air inclosed is moved. As in the meantime the lower end 21 of the oscillating blade 16 is lifted from the curved shape guide 22 the air displaced by the blade 12 can pass through the opening 23 to the outlet socket 20. In the position III shown in Fig. 3 the blade has displaced all the air which entered into the cylinder during the previous rotation and in the meantime the cylinder 2 is filled with fresh air entering through the socket 19. During the further movement of the blade 12 the air must be prevented from passing from the pressure side to the suction side of the blower. This is done by the oscillating blade 16, which, during the further movement of the blade, swings toward the outlet socket, its lower end 21 coming into contact with the correspondingly shaped casing at 22. In the position IV shown in Fig. 3 the oscillating arm 16 has been moved as far as possible toward the outlet socket 20 and begins to return. The end 21 of this arm remains in close contact with the surface 22 of the casing until the parts arrive in the position I shown in Fig. 2, in which position the end 11 of the plate is in contact with the inner surface of the cylinder 1, so that there is then no communication between the pressure side of the casing and the inlet socket 19. The described operation is then repeated.

As no valves of any kind are used in the new blower it can be driven at a very high

speed, and for this purpose, for example, the driving shaft 6 may be coupled directly to an electromotor.

While the blade 12 is moving from the position III in Fig. 3 into the position IV the oscillating blade 16, as above mentioned, will prevent the forced air from passing to the suction side of the blower. During this interval the oscillating blade in close contact with the surface 22 will first be moved toward the outlet socket 20 and then away from the same. Because during the movement of the oscillating blade 16 away from the outlet socket the pressure chamber is enlarged, the forced air may return somewhat during this interval. In order to avoid this I prefer to rigidly connect the blade 16 with a blade 24 provided on the same axis 18. Such a construction is shown in Fig. 5, the oscillating blade 16 and blade 24 being here made in one piece. The end 21 of the arm 16 is as far removed from the axis as the end 25 of the blade 24, which latter is in close contact with the curved shape surface 26. In the position shown at V the blade 16 is nearest to the outlet socket 20. During the further movement of the blade 24 the blade 16, in close contact with the casing at 22, will be moved away from the outlet socket, and at the same time the blade 24 will be moved through the same angle toward the outlet socket 20, the end 25 being then in close contact with the surface 26. As a consequence the size of the pressure chamber remains unaltered and no oscillation of the forced air column can occur.

When the parts have arrived in the dot and dash position shown at VI the end 21 of the blade 16 will begin to rise from the surface 22 and fresh air will be forced by the blade 12 to the outlet socket 20. In the meantime air can pass into the interior 2 of the blower until the blade 12 has cut off communication with the inlet socket. When this has taken place, while the blade 16 still cuts off communication with the outlet socket, the air in the chamber 2 will be compressed during the further movement of the blade 12. In the example shown in Fig. 5 the inner surface of the chamber 2 is prolonged downward by a kind of tongue 27. The farther this tongue reaches, the sooner

will communication between the chamber 2 and the inlet socket 19 be cut off by the blade 12, and the longer it takes from this point before the blade 16 opens communication with the outlet socket 20, the greater will be the compression of the air sucked into the casing. The length of the tongue 27 is however limited by the fact that it must not hinder the oscillating movement of the blade 12. The blade may however be so shaped that the tongue 27 reaches behind the end 11 of the blade as shown in Fig. 5.

What I claim and desire to secure by Letters Patent of the United States is:—

1. The described blower comprising in combination, a casing, a force blade inside said casing, a crank pin adapted to rotate in said casing and carrying one end of said force blade, an oscillating blade hinged to the other end of said force blade, and a blade rigidly connected to said oscillating blade, substantially as and for the purpose set forth.

2. The described blower comprising in combination, a casing, a force blade inside said casing, a crank pin adapted to rotate in said casing and carrying one end of said force blade, an oscillating blade hinged to the other end of said force blade, and a blade of the same radial length as and rigidly connected to said oscillating blade substantially as, and for the purpose, set forth.

3. The described blower comprising in combination, a casing, a force blade inside said casing, a crank pin adapted to rotate in said casing and carrying one end of said force blade, an oscillating blade hinged to the other end of said force blade, a blade rigidly connected to said oscillating blade, and a tongue extending from the upper part of the casing to a point substantially between the pivoted ends of the force blade when in upper position, substantially as and for the purpose set forth.

In testimony whereof, I have signed my name to this specification in the presence of two subscribing witnesses.

JOHANN HUGO AXIEN.
